(57) **CLAIM**

The ornamental design for a wall-mounted connector for a modular power system as shown and described.

DESCRIPTION

FIG. 1 is a perspective view of a wall-mounted connector for a modular power system showing my new design; FIG. 2 is a front view thereof, the rear view being unornamented;

FIG. 3 is a side view thereof, the opposite side view being a mirror image;

FIG. 4 is a top view thereof; and,

FIG. 5 is a bottom view thereof.

In the drawings, the broken lines represent subject matter of the wall-mounted connector for a modular power system that forms no part of the claimed design.
